UNITED STATES PATENT OFFICE.

JOHN R. RANKIN, OF WASHINGTON, DISTRICT OF COLUMBIA.

TYPE-CASE.

No. 901,831.

Specification of Letters Patent.

Patented Oct. 20, 1908.

Application filed March 9, 1908. Serial No. 420,039.

To all whom it may concern:

Be it known that I, JOHN R. RANKIN, a citizen of the United States, residing at Washington, in the District of Columbia, have invented certain new and useful Improvements in Type-Cases; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to the art of printing, and particularly to a type case and stand therefor, and has for its object to provide a device of this class which is so constructed and arranged that the case will accommodate 20 several times the quantity of type as the usual style of case, and which will at the same time accommodate practically an inexhaustible supply of all the logotypes used.

A further object of my invention is to provide 25 a type case which occupies little space and which is extremely simple in construction and cheap and easy to manufacture.

With these objects in view my invention 30 consists in the novel construction of the case and in combination with the stand, all of which will be fully described and afterwards specifically pointed out in the appended claim.

Referring to the accompanying drawing: 35 Figure 1 is a front elevation of the case. Fig. 2 is a side elevation thereof. Fig. 3 is a longitudinal sectional view through the case, and Fig. 4 is a side elevation showing case in vertical position.

40 Like numerals of reference indicate the same parts throughout the several figures in which:

1 indicates the type and logotype case, 2 the cap case and 3 the case stand.

45 As shown in Fig. 1 the case 1 is provided with the usual type boxes 4 arranged in series one above the other, each type box extending rearwardly to form a type reservoir portion 5, while suitable partitions 6 are provided for separating the boxes for the type and logotype.

50 The stand 3 which supports the cases 1 and 2 comprises two vertical uprights 7, two horizontal side pieces 8, two vertical forward supports or legs 9 and a horizontal shelf 10 arranged on top of the vertical uprights 7.

11 indicates a shaft secured under the bottom 12 of the case 1 by means of a clip 13 on each side of the bottom 12 while a suitable bearing or box 14 is provided on each of the 60 side pieces 8 of the stand 3, said bearings or boxes being arranged to receive the shaft 11 as shown in Figs. 2 and 4, and to support the type case 1 in the manner as clearly shown.

On the forward portion of the stand 3 I 65 provide a hinged support 15 for supporting the type case 1 in operative position as shown in Fig. 2, and on each of the vertical uprights 7 I provide a stop 16 for limiting the drop of the type case 1 as shown in dotted lines in 70 Fig. 2.

Referring now to Fig. 4 it will be seen that the type case 1 can be swung upward into a vertical position pivoting on its shaft 11.

17 indicates the cover for the type case 1 75 which, as shown in Fig. 3, is lined with a layer of canvas 18 or other suitable material, the upper and lower edges 19 and 20 being beveled for insertion under the strips 21 on the top of the case 1 and to conform to the 80 front piece 22 of the case 1 as shown in Fig. 3.

When in position shown in Fig. 2, the cap case 2 rests in notches 23 in the strips 21 and leans against the shelf 10. When, however, the type case 1 is in position shown in dotted 85 lines in Fig. 2 or as shown in Fig. 4 the cap case 2 is pushed back upon the shelf 10 as shown in Fig. 4.

Having thus described the several parts of my invention its operation is as follows: In 90 distributing the type and logotype, the same are dropped into the type and logotype boxes 4, and when filled the case 1 is raised into position shown in Fig. 4 which operation allows the type and logotype to drop down into the 95 reservoir portions 5. This operation is repeated until the case is full. During composition the type and logotype are removed from the boxes in the usual manner, and when the boxes become empty the cover 17 100 is arranged on the case as shown in Fig. 3; the cap case 2 is pushed back on the platform 10 and the hinged support 15 is swung forwardly allowing the type and logotype case 1 to drop down into position shown in dotted lines in 105 Fig. 2 striking against the stops 16 with a jar which throws the type and logotype forward filling up all the boxes. The case is then raised into position shown in Fig. 2, the cover 17 removed and the cap case again 110 placed in normal position and the composition continued. This operation requires

only a few seconds, and as it is required only three or four times a day the amount of time saved is at once evident.

A case constructed in accordance with my invention will hold many times the amount of type as an ordinary case including all the usual logotypes with and without spaces on each side, and as every type in the case including logotypes can be picked up with equal facility with the type in the usual cases, the increase in composition is readily apparent.

Having thus fully described my invention what I claim as new and desire to secure by Letters Patent of the United States is:

A case for type, comprising a series of type boxes of a size sufficient to hold a number of type, said type boxes being provided with reservoir portions for holding a large supply of type, a stand upon which the case is pivoted, a support for said case to hold same in

its normal position, said case being pivoted on said stand in such manner that when one or more of the type boxes become depleted the forward portion of the case can be swung down to cause a number of the type in the said reservoir portions to fill the said type boxes, a removable cover for said case arranged to be placed over the said type boxes to prevent the type from falling therefrom when the forward portion of the said case is swung down, the said case being pivoted in such manner that the forward portion thereof can be swung upward to cause the type in said type boxes to pass into the said reservoir portions thereof.

In testimony whereof, I affix my signature, in presence of two witnesses.

JOHN R. RANKIN.

Witnesses:

C. M. FORREST,
C. HUGH DUFFY.
